US0D1074332S

(12) **United States Design Patent** (10) Patent No.: **US D1,074,332 S**
(45) Date of Patent: **** May 13, 2025**

(54) **GRINDER AND FIDGET DEVICE**

(71) Applicant: **DynaVap, LLC**, DeForest, WI (US)

(72) Inventors: **Austin Leasa**, Monona, WI (US); **Troy Sonnleitner**, Sun Prairie, WI (US); **George R. Breiwa, III**, Dane, WI (US)

(73) Assignee: **DynaVap, LLC**, DeForest, WI (US)

(**) Term: **15 Years**

(21) Appl. No.: **29/811,733**

(22) Filed: **Oct. 15, 2021**

(51) LOC (15) Cl. **21-01**

(52) U.S. Cl.

USPC **D7/679**; D21/455; D27/144; D27/172

(57) **CLAIM**

The ornamental design for a grinder and fidget device as shown and described.

DESCRIPTION

FIG. 1 is a plan view of a first side of the grinder and fidget device according to one or more additional examples of embodiments;

FIG. 2 is a first elevation view thereof;

FIG. 3 is a first perspective view of the first side thereof;

FIG. 4 is a second elevation view thereof, rotated 40 degrees from the view shown in FIG. 2;

FIG. 5 is a second perspective view thereof, rotated 40 degrees from the view shown in FIG. 3;

FIG. 6 is a third elevation view thereof, rotated 80 degrees from the view shown in FIG. 2;

FIG. 7 is a third perspective view thereof, rotated 80 degrees from the view shown in FIG. 3;

FIG. 8 is a fourth elevation view thereof, rotated 120 degrees from the view shown in FIG. 2;

FIG. 9 is a fourth perspective view thereof, rotated 120 degrees from the view shown in FIG. 3;

FIG. 10 is a fifth elevation view thereof, rotated 160 degrees from the view shown in FIG. 2;

FIG. 11 is a fifth perspective view thereof, rotated 160 degrees from the view shown in FIG. 3;

FIG. 12 is a sixth elevation view thereof, rotated 200 degrees from the view shown in FIG. 2;

FIG. 13 is a sixth perspective view thereof, rotated 200 degrees from the view shown in FIG. 3;

FIG. 14 is a seventh elevation view thereof, rotated 240 degrees from the view shown in FIG. 2;

FIG. 15 is a seventh perspective view thereof, rotated 240 degrees from the view shown in FIG. 3;

FIG. 16 is an eighth elevation view thereof, rotated 280 degrees from the view shown in FIG. 2;

FIG. 17 is an eighth perspective view thereof, rotated 280 degrees from the view shown in FIG. 3;

FIG. 18 is a ninth elevation view thereof, rotated 320 degrees from the view shown in FIG. 2;

FIG. 19 is a ninth perspective view thereof, rotated 320 degrees from the view shown in FIG. 3;

FIG. 20 is a plan view of a second side thereof;

FIG. 21 is an elevation view thereof;

FIG. 22 is a perspective view of the second side thereof;

FIG. 23 is a second elevation view thereof, rotated 40 degrees from the view shown in FIG. 21;
FIG. 24 is a second perspective view thereof, rotated 40 degrees from the view shown in FIG. 22;
FIG. 25 is a third elevation view thereof, rotated 80 degrees from the view shown in FIG. 21;
FIG. 26 is a third perspective view thereof, rotated 80 degrees from the view shown in FIG. 22;
FIG. 27 is a fourth elevation view thereof, rotated 120 degrees from the view shown in FIG. 21;
FIG. 28 is a fourth perspective view thereof, rotated 120 degrees from the view shown in FIG. 22;
FIG. 29 is a fifth elevation view thereof, rotated 160 degrees from the view shown in FIG. 21;
FIG. 30 is a fifth perspective view thereof, rotated 160 degrees from the view shown in FIG. 22;
FIG. 31 is a sixth elevation view thereof, rotated 200 degrees from the view shown in FIG. 21;

FIG. 32 is a sixth perspective view thereof, rotated 200 degrees from the view shown in FIG. 22;
FIG. 33 is a seventh elevation view thereof, rotated 240 degrees from the view shown in FIG. 21;
FIG. 34 is a seventh perspective view thereof, rotated 240 degrees from the view shown in FIG. 22;
FIG. 35 is an eighth elevation view thereof, rotated 280 degrees from the view shown in FIG. 21;
FIG. 36 is an eighth perspective view thereof, rotated 280 degrees from the view shown in FIG. 22;
FIG. 37 is a ninth elevation view thereof, rotated 320 degrees from the view shown in FIG. 21; and,
FIG. 38 is a ninth perspective view thereof, rotated 320 degrees from the view shown in FIG. 22.
The ornament design which is claimed is shown in solid lines in the drawings. The broken lines in the drawings show portions of the grinder and fidget device which form no part of the claimed design.
